US00D514564S

(12) **United States Design Patent** (10) Patent No.: **US D514,564 S**
Sato et al. (45) Date of Patent: **** Feb. 7, 2006**

(54) **HARD DISK DRIVE**

(75) Inventors: **Toshikuni Sato, Ome (JP); Takahiro Asano, Ome (JP)**

(73) Assignee: **Kabushiki Kaisha Toshiba (JP)**

(**) Term: **14 Years**

(21) Appl. No.: **29/210,208**

(22) Filed: **Jul. 29, 2004**

(30) **Foreign Application Priority Data**

Apr. 20, 2004 (JP) 2004-011920

(51) LOC (8) Cl. **14-02**

(52) U.S. Cl. **D14/363**

(57) **CLAIM**

The ornamental design for a hard disk drive, as shown and described.

DESCRIPTION

FIG. 1 is a front, bottom and right side perspective view of a hard disk drive, showing our new design;

FIG. 2 is a front elevational view thereof;

FIG. 3 is a rear elevational view thereof;

FIG. 4 is a top plan view thereof;

FIG. 5 is a bottom plan view thereof; and,

FIG. 6 is a right side elevational view thereof; a left side elevational view being a mirror image thereof.

1 Claim, 2 Drawing Sheets

FIG. 1

FIG. 4**FIG. 2****FIG. 3****FIG. 6****FIG. 5**
